APPARATUS FOR HANDLING AND ANNEALING METAL BARS OR THE LIKE

John T. Flaherty, Pittsburgh, Pa., assignor to
United Engineering & Foundry Company, Pittsburgh, Pa., a corporation of Pennsylvania

Application July 3, 1935, Serial No. 29,701

24 Claims. (Cl. 80—42)

This invention relates to mechanism for handling metal bars or the like and is more particularly concerned with apparatus for the pack annealing or controlled cooling of merchant bar.

5 In the manufacture of metal bar such as merchant bar it is often desirable to pack anneal them by stacking a plurality of the bars flat side to flat side so that the heat of the metal is retained in the pack whereby an annealing action is obtained. The merchant bar is received from the hot-rolling mill in any particular shape and length and is transported to a pack-annealing bed, where the slow cooling operation is performed.

10 Prior to my invention apparatus has been provided for handling the relatively heavy, long and hot merchant bar and for stacking the bar into annealing packs. Former apparatus have, however, been quite complicated in nature, demanding very considerable initial and maintenance expenditures as well as requiring skilled operators.

15 It is the object of the present invention to avoid and overcome the difficulties attending the use of known apparatus for handling and annealing metal such as merchant bar by the provision of a relatively inexpensive and yet a simple, rugged and durable mechanism which is adapted to rapidly handle hot metal bar of various sizes with the apparatus being adaptable to pack anneal or to individually cool the bars as desired.

20 Another object of the invention is to provide pack-annealing mechanism wherein the annealing operation is continuous with bars being constantly added to one end and removed from the other end of the pack.

25 Another object of the invention is to provide pack-annealing apparatus wherein the bars handled are not scratched in adding them to or removing them from the pack.

30 Another object of the invention is to provide apparatus for handling hot metal bars such as merchant bar wherein by a simple, rapid adjustment the apparatus can be adapted to pack anneal the bars continuously or to lay the bars out individually on a cooling bed without annealing.

35 The foregoing and other objects of the invention are achieved by providing apparatus which includes a hot run-out table, a pack-annealing bed, a cooling bed and a cold run-out table with means positioned between the hot run-out table and the pack-annealing bed for transferring the bars in turn from the table and stacking them on edge in flat-side by flat-side relation on the bed. The transferring means comprises a plurality of rotating cams having recesses for re-

ceiving the bars in turn and for carrying them to the annealing bed. The cams engage with the stacked bars and not only prevent the bars from falling over on the annealing bed but likewise operate to push the end bar of the stack off the annealing bed onto the cooling bed as each hot bar is added to the stack from the run-out table.

40 The apparatus is, moreover, adapted to individually handle and cool bars without pack annealing, and this is accomplished by merely changing the angular position of the annealing bed so that it becomes a part of the cooling bed and receives the bars in spaced cooling relation from the hot run-out table.

45 In the drawings Fig. 1 is a plan view, partly broken away, of one embodiment of my invention; Fig. 2 is a longitudinal vertical cross-sectional view taken on line II—II of Fig. 1; Fig. 3 is a transverse vertical cross-sectional view taken on line III—III of Fig. 1; Fig. 4 is a view similar to Fig. 2 but illustrates the pack-annealing bed of the apparatus tipped to the position where the apparatus operates to individually cool the bars; Fig. 5 is a view similar to Figs. 2 and 4 but illustrates a modification of the invention wherein means are provided for handling of the bars without chance for surface scratching; and Fig. 6 is a side elevation of the cam transfer means incorporated in the invention.

50 While the apparatus is adapted to handle various strip and bar materials it is particularly designed for the handling and/or pack annealing of metal merchant bar of various shapes and sizes. Merchant bar is ordinarily rectangular in cross section and accordingly the apparatus is illustrated and described as handling rectangular bar.

55 The rectangular bar is, for example, from 2 to 12 inches wide to from $\frac{1}{8}$ up to 2 inches thick. Its length varies considerably, as, for example, from 100 feet to 300 feet more or less. It should also be understood however that bar of other shapes such as rounds, squares, angles, etc. can be handled. In view of the widely varying shapes and dimensions of merchant bar, the present apparatus can be made in any particular size but is preferably constructed to handle the largest sizes and when this is done the mechanism also operates with smaller-sized bars.

60 Since the merchant-bar handling apparatus is often so long, and because the apparatus of the present invention for handling this bar is duplicated at axially spaced areas across the length of the various run-out tables and the annealing and cooling beds, the plan view of the drawings

has been broken away after illustrating several of the similar means for effecting handling and annealing of the bar.

As best seen in Figs. 1 to 3, the invention 5 includes a hot run-out table, indicated generally by the numeral 10, a pack-annealing bed, shown generally at 12, a cooling bed, indicated generally at 14, and a cold run-out table, indicated generally by the numeral 16. An important 10 feature of the invention is the transfer means, shown generally at 18, for carrying the merchant bar from the hot run-out conveyor 10 to the pack-annealing bed 12.

The hot run-out table 10 is adapted to receive 15 the hot merchant bar from the rolling mill and operates to convey merchant bar B to the transfer means 18 for placing the bar on the annealing bed. The hot run-out table 10 may take a plurality of forms but preferably comprises a 20 base 20 having rollers 21 journaled thereon and driven by suitable means, such as individual motors 22. Associated with the side of the hot run-out table 10 are laterally extending inclined skids 23 which function to receive the merchant 25 bar B from the hot run-out table.

Suitable means are provided for laterally moving the bar B from the hot run-out table 10 onto the skids 23, and this means may include 30 a crank shaft 25 journaled in the base 20 and having crank portions 26 carried in bearings 27 formed on pusher arms 28. The lower end of each pusher arm 28 is pivotally connected, as at 29, to a link 30 pivotally secured to a bracket 31 fixed to the base 20. The crank shaft 25 is 35 driven in any preferred manner as, for example, by a motor 32 through a gear box 33. Thus when motor 32 is driven to turn crank shaft 25, each pusher arm 28 moves from its retarded full-line position, seen in Fig. 2, up to and past 40 the dotted-line position, likewise shown in this figure, to push the merchant bar B onto the inclined skids 23.

Positioned adjacent the lower end of the skids 23 are the transfer means, shown generally at 45 18, which includes a plurality of cams 35 preferably mounted upon a common shaft 36 driven by suitable means such as motor 37 through a gear box 34. Each cam 35, as best seen in Fig. 6, is formed with one or more recesses 38, preferably 50 having a flat surface, with the recesses being adapted to receive the merchant bar B from the inclined skids 23. From the point 39 at one side of the recess 38 to a point approximately at 40 the cam gradually builds up on a steadily increasing 55 radius so that the distance from the point 40 to the axis of the cam is greater than the distance from the point 39 to the axis of the cam by substantially the thickness of the thickest bar to be handled by the apparatus. From the point 60 40 to the point 41 on the cam, the surface of the cam is formed on a constant radius terminating in the shoulder 42. As stated, the cams may be formed with any number of recesses. In the embodiment of the invention illustrated, however, two recesses 38 are provided on each cam with the points 39, 40, 41 and the shoulder 42 being duplicated on the other half of the cam surface as illustrated in Fig. 6.

Preferably, the cams 35 are employed in groups 70 at spaced intervals along the shaft 36, as best seen in Fig. 1. The distance between each group of cams on the shaft 36 is somewhat less than the shortest bar to be handled, so that, in transferring the bar by the cams, more than one group 75 carries the bar regardless of its length. The

recesses 38 on each cam and upon the several groups are, of course, aligned axially to this end. While, as indicated, each group consists of three cams having narrow faces it should be understood that a single cam having a face of any 5 desired width may be used.

The shaft 36, carrying the cams 35, is journaled in suitable bearings 45 which, together with the remaining apparatus, are positioned to bring the recesses 38 of the cams 35 just below 10 the surface of the inclined skids 23, as illustrated in Fig. 2, so that in the operation of the transfer mechanism the bars B pushed off of the hot run-out table slide down the inclined skids 23 and against the shoulders 42 at one side of 15 the recesses 38 formed in the cam. The shoulders 42 thus act as positive stops which together with the momentum of the hot bars serve to straighten them to remove curves or kinks formed in rolling. The skids 23 are set at such an angle 20 and made of the requisite length whereby the desired straightening action is obtained. It will be evident that the merchant bar B is moved onto the cams 35 in substantially a tangential manner and at substantially the highest point of 25 the cam.

Associated with the other side of the transfer cams 35 is the pack-annealing bed heretofore discussed and shown generally by the numeral 12. This pack-annealing bed includes a plurality of platforms generally formed with longitudinally extending bars 50 connected together by integral spacers 51. The platforms are provided with portions 52 which extend radially inwardly of the cams 35 and which operate to receive 35 the bars B from the transfer cams 35 as hereafter more fully discussed. The platforms of the annealing bed 12 are preferably pivotally mounted upon a shaft 54 and have a lever 55 pivotally secured as at 56 to the end of the platform with 40 the other end of the lever 55 being provided with a bearing 57 surrounding an eccentric 58 carried by a shaft 59 whereby the angular position of the annealing beds can be controlled.

Ordinarily, as shown in Fig. 2, the annealing 45 beds 12 are inclined oppositely to the inclined skids 23 and thus provide a surface extending substantially radially to the transfer cams 35. Thus, in the operation of the apparatus, the merchant bars B received by the recesses 38 of the 50 cams from the inclined skids 23 are, upon rotation of the cams, carried down to the annealing bed through a relatively short arc and are deposited on edge on the bed in pack-annealing relation, that is flat side to flat side, as shown in 55 Fig. 2.

It should be understood that in operation the transfer cams 35 engage with the bars B already on the pack-annealing bed 12 and that the cams prevent the bars from falling over. Likewise, the 60 cams function to move the entire pack of bars upwardly upon the inclined annealing bed as the cams gradually build up to the shoulders 42. Thus the rotation of the cam with a new bar 65 nested in the recess 38 causes the new bar to be added to the bottom or lower end of the pack, with the projection 52 of each platform of the annealing bed picking the bar off the cams.

The movement of the cams 35 and the addition of bars B to the pack on the annealing bed 70 can be continuous or intermittent as desired. Ordinarily, the motors 32 and 37 are provided with push-button controls so that the operator handling the apparatus can control the pack-annealing 75 operation as desired dependent, of course,

upon the number and size of merchant bars fed to the hot run-out table 10. If desired the operation of the apparatus can be intermittent, with the cams 35 being stopped each time in 5 the bar-receiving position shown in Fig. 2 as, for example, by the use of a limit switch on the shaft 36. The cams stay in this position until a bar B is moved laterally off the hot run-out table by the pushers 28 with the bar sliding down inclined skids 10 23 and into the cam recess 38. At this time the operator starts motor 37 to transfer the bar to the pack-annealing bed.

After the pack has built up to cover the entire annealing bed and as each hot bar is added to 15 the lower end of the annealing pack, an annealed bar is pushed off the sloping end 60 of the annealing bed 12 onto the cooling bed 14 where it is received in flat position. The cooling bed 14 is of any suitable construction but preferably comprises a shuffle-bar type of cooling bed having a 20 base 61 supporting a plurality of bars 62 connected by integral spacers 63. The bars 62 of the cooling bed, as shown in Fig. 1, extend in between the ends of the bars 50 of the pack-annealing bed 12 25 so that full support for the merchant bar B carried over the beds is afforded. The cooling beds 14 are provided with shuffle bars 65 slidably carried on rollers 66 riding upon tracks 67 mounted upon the base 61 of the cooling bed 14. Each 30 shuffle bar 65 is provided with ducking dogs 70 at spaced points which are pivotally secured, as at 71, to the bars 65 and which have heavy back portions 72 normally holding the dogs 70 with a perpendicular face extending above the surface of 35 the bars 62, as best seen in Fig. 3.

The shuffle bars 65 are adapted to be reciprocated forward and back upon the tracks 67 and in the embodiment of the invention illustrated this is accomplished by the provision of a rocking 40 shaft 75 carrying cranks 76 and adjustable length connecting rods 77 which are pivotally secured to the shuffle bars 65. In the backward movement of the shuffle bar the dogs 70 duck or tip to pass underneath the merchant bar B lying on 45 the cooling bed. However, in the forward movement of the shuffle bar, the heavier portions 72 of the dogs bring the dogs back to vertical position, and because the dogs only tilt in one direction they engage behind the merchant bar B and move 50 the bars forward a feeding step. Thus, each oscillation of the rock shaft 75 feeds the merchant bars B on the cooling bed 14 forward one step.

Positioned at the end of the cooling bed 14 is the cold run-out table 16 and this may comprise 55 a base 80 having a plurality of rollers 82 journaled thereon and driven by any suitable means as, for example, a shaft 83 connected to a motor 84. Since the shuffle bar mechanism of the cold run-out table 14 ordinarily is not designed to feed 60 the merchant bar B completely onto the cold run-out table 16, additional means are provided for achieving this result. These means, in the form of the invention illustrated, are duplicated at spaced areas and each includes a ducking dog 65 86 pivotally carried in a bracket 87 secured to a rod 88 extending transversely of the cold run-out table 16 and into the end of the cooling bed 14. The rod 88 is secured to a bracket 89 fixed on a rack 90 with a pinion 91, driven by a shaft 92 70 connected to a motor 93, serving to control the position of the rack. Thus, operation of the motor 93 moves the ducking dogs 86 toward the cold run-out table 16 to move the merchant bar B from the cooling bed 14 completely onto the 75 rollers 82 of the cold run-out table 16.

A novel feature of the invention is that the apparatus can be readily adapted to handle metal bar without subjecting it to pack annealing. For example, a controlled cooling operation can be performed without stacking the bars in flat-side 5 by flat-side relation. This is readily accomplished, as illustrated in Fig. 4, by tilting the pack-annealing bed 12 to horizontal position by operation of the shaft 59 which controls the angular position of the annealing bed. When the bed is horizontal it aligns itself substantially flush with the surface of the usual cooling bed, and, by moving the cams 35 through a small arc to the position shown in solid lines in Fig. 4, merchant 10 bar sliding down the inclined skids 23 moves directly onto the top of the pack-annealing bed 12. The merchant bar is shown round in section in 15 this embodiment of the invention. By then slightly increasing the stroke or the initial position of the shuffle bars 65 of the cooling bed 14, 20 the bars received on the pack-annealing bed 12 are carried across the pack-annealing bed and the cooling bed in a step-feeding operation with the pack-annealing bed operating substantially as a continuation or extension of the usual cooling bed. The transfer mechanism, including the cams 35, need not be employed when using the apparatus for controlled cooling as just described. However the cams 35 may be positioned in the dotted position in Fig. 4 so that the shoulders 30 42 operate as positive stops to straighten the bar as heretofore described. After each bar stopping and straightening operation the cams are rotated through approximately 180° to allow the straightened bar to roll onto the cooling bed and 35 to bring the next cam shoulder 42 into position to receive the next bar.

In the ordinary operation of the apparatus for pack annealing merchant bar it will be evident that there is a sliding movement of the cams 35 40 over the end bar of the annealing pack which not only serves to hold the bars from falling over on the annealing bed but which likewise moves the complete pack upwardly on the inclined annealing bed in order to make room for the next bar 45 to be fed to the pack. This sliding movement of the cams over the end bar is ordinarily not attended with undesirable marring of the bar but in certain instances, where high-surface finish on the bars is requisite, it may slightly disfigure the 50 surface, particularly where heavy bar is handled with a pack of considerable thickness being built up on the annealing bed. In order to overcome any surface scratching from the movement of the cam surfaces over the end bar of the annealing 55 pack, mechanism is provided for pushing the pack upwardly on the annealing bed with a direct thrust, with the cam means operating solely to transfer the new bars to the pack.

Thus, in Fig. 5 is illustrated suitable mechanism for moving the pack by direct thrust. This mechanism includes cams 100 mounted upon the same shaft 36 as carries the cams 35 but to one side thereof. The cams 100 have high portions substantially at right angles to the recesses 38 of 60 the cams 35. Surrounding each cam 100 is a yoke 101 carrying a roller 102 which engages with the cam 100. The yoke 101 is formed with a stud extension 103 slidably carried in cylinder 104 fixed to the base 20, with tension spring means 105 positioned in the cylinder and serving to resiliently pull the stud 103 of the yoke 101 into the cylinder 104 and thus cause the roller 102 on the yoke to follow the cam 100.

The yoke 101 is also provided with an integral 75

pusher 107 which is adapted to engage with the last bar of the pack on the annealing bed as the roller 102 rides over the high portion of the cam 100 to thereby move the pack upwardly on the annealing bed by direct positive thrust. However, when the roller 102 of the yoke rides on the low portion of cam 100 the tension spring 105 pulls the yoke back so that the portion 107 of the yoke lies radially within the recess 38 formed on the cams 35.

Thus in the operation of the mechanism just described, with the parts in the position shown in Fig. 5, the pack has just been pushed up on the annealing bed by cam 100 with the yoke 101 then being rapidly retarded and with the cams 35 functioning to merely prevent the bars from falling over on the table. The continued rotation of the transfer cams 35 brings the next bar down into position against the end of the pack and, during this placing of the bar on the pack, the yoke remains in the retarded position. Continued rotation of the shaft 36 causes the outward movement of the yoke to again push the pack up on the annealing bed so that another bar can be added to the lower end of the pack as just described.

In the particular form of the invention shown in Fig. 5 a somewhat different type of pack-annealing bed is illustrated as including platforms 30 pivotally mounted on a shaft 110 fixed in a base 111. The inclined position of the annealing bed is controlled by a shaft 112 carrying an eccentric 113 surrounded by a bearing 114 carried by a connecting lever 115.

Of course, the invention contemplates employing the direct-thrust pack-moving mechanism shown in Fig. 5 directly with the transfer mechanism shown in Figs. 1 to 4 and with either type of pack-annealing bed disclosed.

It is believed that the operation of the apparatus will be completely understood from the foregoing description. However, briefly, the operation consists in moving in hot metal bar B one at a time on the hot run-out table 10 with the bars 45 being laterally discharged from the table 10 by the pusher bars 28. The inclined skids 23 receive the bars from the hot run-out table, and the bars move by gravity into the recesses 38 formed in the cams 35 of the transfer mechanism shown generally at 18. The transfer cams 35 carry the bars B in turn to the pack-annealing bed where the bars are deposited on edge in flat-side by flat-side relation. As each bar is added to the bottom or lower end of the annealing pack one is pushed 55 off the upper end of the pack and slides down in flat position upon the cooling bed 14. The shuffle bars 65 carrying the ducking dogs 70 on the cooling bed move the bars in step-by-step relation along the cooling bed as the shuffle bars are reciprocated. As the bars B near the end of the cooling bed 14 they are moved onto the cold run-out table shown generally at 16 by the ducking dog 86 operated by the rod 88, rack 90 and pinion 91.

If it is desired to employ the apparatus solely for handling of hot metal bars, and more particularly for the cooling of the bars, the position of the pack-annealing bed can be rapidly changed to adapt the mechanism to pass the bars in spaced step-by-step relation across a continuous cooling bed. Likewise, the apparatus can be constructed to handle the pack annealing of merchant bar without surface scratching of the bar.

The stated objects of the invention are achieved by the apparatus just described in that the annealing and handling mechanism is quite simple,

rugged and inexpensive in initial and maintenance cost as compared with the complicated pack-annealing mechanisms known heretofore. Moreover, my apparatus is designed to handle merchant bar of substantially any size and shape without modification of the apparatus, and the handling and transferring of the bars, as well as the piling for pack annealing, is more rapid and positive than obtained with prior apparatus. The pack-annealing operation, as well as the cooling operation, can be substantially continuous and can be controlled by a minimum number of operators who require no special training.

While, in accordance with the patent statutes, several embodiments of the invention have been illustrated and described in detail, it should be understood that the invention is not limited thereto or thereby but is defined in the appended claims.

I claim:

1. Apparatus for handling merchant bar comprising a hot run-out table, a pack-annealing bed, a cooling bed, a cold run-out table, and means positioned between the hot run-out table and the pack-annealing bed for transferring the bars in turn from the hot run-out table and stacking them on the annealing bed, said means including a plurality of rotating cams having notches for receiving the bars in turn and carrying them to the annealing bed, said cams operating with a wiping cam action to push the end bar of the stack off the annealing bed onto the cooling bed as each hot bar is added to the stack from the hot run-out table.

2. Apparatus for handling merchant bar comprising a hot run-out table, an inclined pack-annealing bed, and means positioned between the hot run-out table and the pack-annealing bed for transferring the bars in turn from the table and stacking them on the bed, said means including a plurality of rotating cams having recesses for receiving the bars in turn and carrying them to the lower end of the annealing bed, said cams holding the stacked bars against sliding down on the annealing bed and likewise operating to push the end bar of the stack off the upper end of the annealing bed as each hot bar is added to the stack from the run-out table.

3. Apparatus for handling merchant bar comprising a hot run-out table, a pack-annealing bed, means positioned between the hot run-out table and the pack-annealing bed for transferring the bars in turn from the table and stacking them on the bed, said means including a plurality of rotating cams having recesses for receiving the bars in turn and carrying them to the annealing bed; said cams holding the stacked bars from falling over on the annealing bed and mechanism for moving the stack of bars over the annealing bed to discharge the end bar from the stack opposite the transfer means.

4. The combination recited in claim 3 wherein further the mechanism provided for moving the stack of bars over the annealing bed includes a driven shaft, a plurality of cams mounted on the shaft, and yokes surrounding the shaft and engaging with the cams, said yokes contacting with the stack to move it when the high portions of the cams engage with the yokes.

5. In combination, an inclined conveyor for moving merchant bar laterally, an oppositely inclined annealing bed for laterally receiving the bar, a rotatable cam having a recess formed on its surface for receiving the bars in turn and for carrying them to and depositing them on edge on

- the annealing bed, the upper surface of the inclined conveyor being substantially tangent to the recess on the cam, the oppositely inclined annealing bed surface extending substantially radially of the cam and having portions extending radially inwardly of the cam surface, the lower end of the surface of the inclined annealing bed being lower than the inclined conveyor, and means for changing the inclination of the annealing bed to bring it into position for receiving the bar directly from the inclined conveyor.
6. In combination, an inclined conveyor for moving merchant bar laterally, an oppositely inclined annealing bed for laterally receiving the bar, a rotatable cam having a recess formed on its surface for receiving the bars in turn and for carrying them to and depositing them on the annealing bed, the upper surface of the inclined conveyor being substantially tangent to the recess on the cam, the oppositely inclined annealing bed surface extending substantially radially of the cam and having portions extending radially inwardly of the cam surface, and the lower end of the surface of the inclined annealing bed being lower than the inclined conveyor.
7. In combination, an inclined conveyor for moving merchant bar laterally, an oppositely inclined annealing bed for laterally receiving the bar, and a rotatable cam having a recess formed on its surface functioning as a bar straightening stop and for receiving the bars in turn and for carrying them to and depositing them on the annealing bed, the upper surface of the inclined conveyor being substantially tangent to the recess on the cam, and the oppositely inclined annealing bed surface extending substantially radially of the cam.
8. In combination, an inclined conveyor for moving merchant bar laterally, an oppositely inclined annealing bed for laterally receiving the bar, and a rotatable cam having a recess formed on its surface for receiving the bars in turn and for carrying them to and depositing them on the annealing bed to form a pack.
- 45 9. In combination, an inclined conveyor for moving merchant bar laterally, an oppositely inclined annealing bed for laterally receiving the bar, and a rotatable cam turning in one direction and having a plurality of recesses formed on its surface for receiving the bars in turn and for carrying them to the annealing bed.
10. In combination, an inclined conveyor for moving merchant bar laterally, an oppositely inclined annealing bed for laterally receiving the bar, a rotatable cam positioned in the valley formed between the conveyor and bed, said cam having a recess formed on its surface for receiving the bars in turn and for carrying them to and depositing them on edge on the annealing bed, and means for changing the inclination of the annealing bed to bring it into position for receiving the bar directly and in flat cooling position from the inclined conveyor without the use of the rotatable cam.
- 65 11. Apparatus for pack annealing merchant bar comprising a plurality of cams mounted in axially spaced positions on a rotatable shaft, each cam being formed with a gradually built-up portion extending over a considerable arc and ending in a radial shoulder forming a recess below the surface of the cam for receiving a bar with the cam then being built up again to a shoulder and recess, said shoulders being aligned on the axially spaced cams, means for tangentially moving a bar into the aligned recesses when they are substantially at the most upward position in the rotation of the cam, and means for removing the bar on edge from the cams after the rotation thereof of approximately ninety degrees, said cams engaging the bar after it is on the removing means and holding it against falling over, with the built-up portions of the cams moving the bar along the removing means so that another bar can be removed by the removing means.
12. Apparatus for pack annealing merchant bar comprising a plurality of cams mounted in axially spaced positions on a rotatable shaft, each cam being formed with a gradually built-up portion extending over an arc of at least ninety degrees and ending in a radial shoulder forming a recess for receiving a bar with the cam then being built up again to a shoulder, said shoulders being aligned on the axially spaced cams, means for moving the merchant bar along its longitudinal axes to a point adjacent the transfer cams, means for laterally moving a bar into the aligned recesses, and means for removing the bar on edge from the cams, said cams engaging the bar after it is on the removing means and holding it against falling over, with the built-up portions of the cams moving the bar along the removing means so that another bar can be removed by the removing means.
13. Apparatus for pack annealing merchant bar comprising a plurality of cams mounted in axially spaced positions on a rotatable shaft, each cam being formed with a gradually built-up portion ending in a radial shoulder forming a recess for receiving a bar with the cam then being built up again to a shoulder, said shoulders being aligned on the axially spaced cams, means for tangentially moving a bar into the aligned recesses when they are substantially at the most upward position in the rotation of the cam, means for removing the bar on edge from the cams after the rotation thereof of approximately ninety degrees, said cams engaging the bar after it is on the removing means and holding it against falling over, and mechanism other than the cams for moving the bar along the removing means so that another bar can be removed by the removing means.
14. In combination, a hot run-out table, an inclined slide positioned at the side of the table, a pack-annealing bed adjacent the slide, means for moving merchant bars in turn laterally off the hot run-out table onto the slide, rotary cam means for transferring the bars in turn from the slide onto the annealing bed and serving to hold the bars on the bed and likewise to move the bars along the bed, a shuffle dog cooling bed for receiving the bars from the annealing bed, a cold run-out table for conveying the bars from the cooling bed, means for changing the position of the annealing bed to cause it to receive the bars in flat position directly from the slide, and means for reciprocating the shuffle dogs of the cooling bed whereby the bars will be moved in spaced relation over the annealing and cooling beds to the cold run-out table.
15. In combination, a hot run-out table, an inclined slide positioned at the side of the table, a pack-annealing bed adjacent the lower end of the slide, means for moving bar laterally off the hot run-out table onto the slide, means for transferring the bar from the slide onto the annealing bed and serving to move the bar along the bed and continuously support the bars thereon even during the movement of another bar from the slide to the annealing bed, a shuffle bar cooling

bed for receiving the bar from the annealing bed, and a cold run-out table for conveying the bar from the cooling bed.

16. Mechanism for pack annealing merchant bar including an inclined annealing bed, means for conveying bars in turn to a point adjacent the bed, and transfer means including a rotatable cam for moving the bars in turn from the conveying means to the annealing bed and stacking the bars on edge on the bed to form a pack, the cam constantly engaging with the last bar added to the pack and operating to hold the pack up and to move the pack along on the bed so that as each bar is added at one end of the pack one is moved off the bed at the other.

17. Mechanism for pack annealing merchant bar including an annealing bed, means for conveying bars in turn to a point adjacent the bed, and transfer means for moving the bars in turn from the conveying means to the annealing bed and stacking the bars on edge on the bed to form a pack, said last-named means continuously functioning as a stop at one end of the pack throughout the entire operation of the mechanism.

18. Apparatus for handling and annealing merchant bar comprising an annealing bed adapted to support a pack of bars formed by placing them on edge and flat side to flat side, a cam adjacent one end of the bed and adapted to engage with the last bar of the pack, said cam gradually building up circumferentially to a recess adapted to receive a bar, means for turning the cam in one direction so that rotation of the cam moves the pack along the bed and moves the bar of the far end of the pack off the bed while the recess carrying an additional bar deposits it on edge on the bed in the near end of the pack.

19. Apparatus for handling metal comprising a hot run-out table, an inclined annealing bed, a horizontal cooling bed, a transfer mechanism for moving the metal from the table to the annealing bed, and means for turning the annealing bed into alignment with the cooling bed so that the metal moves directly to the combined cooling and annealing bed from the run-out table without handling by the transfer mechanism.

20. The combination recited in claim 19 wherein further the transfer mechanism can be adapted to function as a metal straightening stop in either a cooling or a pack annealing operation when the metal strikes it during the transfer operation.

21. In combination, a conveyor for moving merchant bar laterally, an inclined annealing bed for laterally receiving the bar, a rotatable cam positioned between the conveyor and bed, said cam having a recess formed on its surface for receiving the bars in turn and for carrying them to and depositing them on edge on the annealing bed, and means for changing the inclination of the annealing bed to bring it into position for receiving the bar directly and in flat cooling position from the inclined conveyor without the use of the rotatable cam.

22. Apparatus for pack-annealing merchant bar comprising a hot run-out table, inclined skids positioned laterally of the table, means for moving the bar from the table onto the skids, an oppositely inclined annealing bed adjacent the lower ends of the skids, rotatable transfer means positioned in the valley between the skids and the bed for receiving the bar from the skids and depositing it on edge on the bed, the transfer means acting as a stop at the lower end of the annealing bed for supporting the bars on edge thereon and means for periodically causing relative movement of the annealing bed and the bars on the annealing bed to force a bar off the end of the bed opposite the transfer means.

23. Apparatus for pack annealing merchant bar comprising a hot run-out table, inclined skids positioned laterally of the table, means for moving the bar from the table onto the skids, an annealing bed adjacent the lower ends of the skids, rotatable transfer means positioned between the skids and the bed for receiving the bar from the skids and depositing it on edge on the bed, the transfer means acting as a stop at the end of the annealing bed for supporting the bars on edge thereon and means for periodically causing relative movement of the annealing bed and the bars on the annealing bed to force a bar off the end of the bed opposite the transfer means.

24. Apparatus for pack annealing merchant bar comprising a hot run-out table, an annealing bed adjacent the table, transfer means positioned between the table and the bed for receiving the bar from the table and depositing it on edge on the bed, the transfer means acting as a stop at the end of the annealing bed for supporting the bars thereon and means for periodically causing relative movement of the annealing bed and the bars on the annealing bed to force a bar off the end of the bed opposite the transfer means.
